US0D1066508S

(12) **United States Design Patent** (10) **Patent No.:** **US D1,066,508 S**
Berman et al. (45) **Date of Patent:** **** Mar. 11, 2025**

(54) **GAMING APPARATUS HAVING DISPLAY SCREEN WITH GRAPHICAL USER INTERFACE**

(71) Applicant: **King Show Games, Inc.**, Minnetonka, MN (US)

(72) Inventors: **Bradley Berman**, Minnetonka, MN (US); **Chad Shapiro**, Plymouth, MN (US); **Ryan Strand**, Hopkins, MN (US)

(**) Term: **15 Years**

(21) Appl. No.: **29/669,161**

(22) Filed: **Nov. 6, 2018**

Related U.S. Application Data

(63) Continuation-in-part of application No. 29/600,466, filed on Apr. 12, 2017, now abandoned, which is a continuation of application No. 29/448,307, filed on Mar. 11, 2013, now Pat. No. Des. 793,409, application No. 29/669,161, filed on Nov. 6, 2018 is a continuation-in-part of application No. 14/177,636, filed on Feb. 11, 2014, now Pat. No. 10,600,288.

(57) **CLAIM**

The ornamental design for a gaming apparatus having display screen with graphical user interface as shown and described.

DESCRIPTION

The FIGURE is a front view of a gaming apparatus having display screen with graphical user interface showing the new design.

The outermost solid-line rectangle illustrates the perimeter of the display screen of the gaming apparatus. The broken lines outside this perimeter show portions of the gaming apparatus. The broken lines within this perimeter show portions of the graphical user interface. The broken lines form no part of the claimed design.

1 Claim, 1 Drawing Sheet
